UNITED STATES PATENT OFFICE

170,258

PIE

Howard L. Griffin, Greensboro, N. C.

Application June 12, 1952, Serial No. 20,158

Term of patent 14 years

(Cl. D8—1)

To all whom it may concern:

Be it known that I, Howard L. Griffin, a citizen of the United States, residing at Greensboro, in the county of Guilford and State of North Carolina, have invented a new, original, and ornamental Design for a Pie, of which the following is a specification, reference being had to the accompanying drawing, forming part thereof, in which:

Fig. 1 is a top perspective view of a pie showing my new design;

Fig. 2 is a top plan view of the pie shown in Fig. 1;

Fig. 3 is a bottom plan view;

Fig. 4 is a side elevational view, and

Fig. 5 is an end elevational view thereof.

I claim:

The ornamental design for a pie, substantially as shown.

HOWARD L. GRIFFIN.
